UNITED STATES PATENT OFFICE.

DALLAS RICH MCKAY, OF OAK PARK, ILLINOIS, ASSIGNOR TO IMPERIAL BELTING COMPANY, OF CHICAGO, ILLINOIS.

COMBINATION SHIPPING CASE AND BELT REEL.

Application filed January 31, 1927. Serial No. 164,908.

My invention relates to improvements in combination shipping cases and belt reels, and it consists in the combinations, constructions, and arrangements herein described and 5 claimed.

An object of my invention is to provide a combination shipping case and belt reel which permits the convenient and economical handling of large rolls of belting.

10 A further object is to provide a device of the type described which makes it possible for the customer to buy belting material in larger quantities and at a lower cost.

15 A further object is to provide a device of the type described which obviates the need of hoists and other equipment ordinarily used in raising the roll of belting material into a rotatable position.

20 A further object is to provide a device of the type described which provides a novel means for holding the roll of material against displacement within the case during importing and exporting.

25 A further object is to provide a device of the type described in which the casing serves as a shipping crate, as a guide for the belting, and as a support for the roll of belting material.

30 Other objects and advantages will appear in the following specification, and the novel features of the invention will be particularly pointed out in the appended claims.

35 My invention is illustrated in the accompanying drawings, forming part of this application, in which

Figure 1 is a side elevation of my device,

Figure 2 is a section substantially along the line 2—2 of Figure 1,

40 Figure 3 is a side elevation of my device with the roll of material in rotative position, and

Figure 4 is a side elevation of the device when ready for exporting.

45 In carrying out my invention, I provide a casing A having side walls 1 and 2, end walls 3 and 4, a top 5, and a bottom 6.

50 The sides 1 and 2 are provided with horizontally extending reinforcing members 7 and 8, respectively, which are rigidly secured to relatively long vertically extending reinforcing members 9, and relatively short reinforcing members 10. The sides 1 and 2 are further provided with reinforcing strips 11 and 12. Blocks 13 are disposed upon the reinforcing strip 12 substantially adjacent the

bottom 6 and are provided with openings 14 for receiving bars 14'. A roll of material 15, having a central opening 16, is disposed within the casing A upon the bars 14'.

When the roll of material is disposed within the casing and the walls thereof properly secured in place, the device is ready to be delivered to the customer. The customer may then remove one of the end walls. A shaft or axle 17 may then be passed through 65 rectangular openings 18 which are provided in the side walls 1 and 2 and through the central opening 16. The shaft 17 extends a short distance beyond the casing, see Figure 2. By placing jacks or other suitable means 70 beneath the ends of the shaft 17, the roll 15, together with the shaft 17, may be raised a short distance to free the roll from the bars 14'. When the roll 15 has been raised the desired distance, pillow blocks 19, having 75 arcuate-shaped grooves 20 in the upper surface thereof, are disposed upon the horizontally-extending members 7 and 8 beneath the shaft 17. By removing the jacks or other suitable raising means, the shaft 17 80 will rest upon the pillow blocks 19. The roll 15 may now be rotated upon the shaft 17. The reinforcing members and strips are of sufficient strength to support the roll. The shaft 17, together with the pillow blocks 85 which are not used when the device is delivered, may be enclosed within the casing A.

In Figure 4 I have shown the casing prepared for exporting. In exporting, it is necessary to provide means for rigidly holding the roll in one fixed position within the casing whereby the roll cannot move therewithin. The reason for this is that the large rolls of material, such as belting, weigh approximately three thousand pounds, and, if 95 the rolls were permitted to move within the casing, the casing would be easily damaged. This means consists in providing additional reinforcing strips 21 upon each side thereof which have openings 22 for receiving bars 100 23. The bars 23, together with the bars 14', rigidly hold the roll at four points upon the circumference thereof.

I claim:

1. A device of the type described, comprising a casing having openings therein and adapted to receive a roll of material having a central opening therethrough, reinforcing means for said casing, a shaft receivable in said openings, and means dis- 105 110

posed upon said reinforcing means for supporting said shaft and said roll.

2. A device of the type described, comprising a casing adapted to receive a roll of material, reinforcing means for said casing having openings therethrough, and bars receivable in said openings and adapted to engage with said roll of material at spaced-apart points upon the peripheral edge thereof, whereby said roll is held against displacement within said casing.

3. A device of the type described, comprising a casing having openings therein and adapted to receive a roll of material having a central opening therethrough, reinforcing means for said casing, means for holding said roll against displacement, a shaft receivable within said openings, said shaft and said roll being adapted to be raised when said holding means are removed, and means cooperating with said reinforcing means for supporting said shaft and said roll in rotative position.

4. A device of the type described comprising a casing adapted to receive a roll of material and having an opening therethrough, means carried by said casing for supporting the roll of material for holding the roll of material against displacement when said casing is in one position, and means adapted to extend through said opening for rotatably supporting the roll of ma-

terial when the roll of material has been freed from said supporting means.

5. A device of the type described comprising a casing having an opening therein and adapted to receive a roll of material having a central opening therethrough, means extending through said casing for holding said roll of material against displacement, said means consisting of rods disposed adjacent the periphery of said roll of material, said roll of material being adapted to be moved free from said rods, and a shaft disposed within the opening in said casing and the opening in said roll of material for rotatably carrying said roll of material.

6. A device of the type described comprising a casing having an opening therein and adapted to receive a roll of material having a central opening therethrough, means extending through said casing for holding said roll of material against displacement, said means consisting of rods disposed adjacent the periphery of said roll of material, said roll of material being adapted to be moved free from said rods, a shaft disposed within the opening in said casing and the opening in said roll of material for rotatably carrying said roll of material, and shaft-receiving means carried by said casing for supporting said shaft.

DALLAS R. MCKAY.
